Application May 19, 1944, Serial No. 536,244

3 Claims. (Cl. 114—117)

1

This invention relates to water-tight or gas-tight closures for openings in ships' bulkheads, decks and also walls. It has for its principal objects the provision of a closure of that character which is of simple, compact and economical construction and which is equipped with sturdy locking mechanism that is quick-acting and convenient as well as easy to manipulate, besides being substantially free from external projections which tend, in the case of a bulkhead door for example, to obstruct an adjacent corridor or passage way or be otherwise objectionable. Furthermore, such locking mechanism is so disposed that not only is the same substantially entirely concealed within or behind the closure and its frame when the former is shut tight against the latter but the main panel of the closure constitutes an effective seal and no portion of the locking mechanism projects beyond the same. Other objects of the invention will hereinafter appear.

It has been heretofore proposed, as set forth for example in U. S. Patents No. 2,197,824, of April 23, 1940; No. 1,416,308, of May 16, 1922; and No. 2,278,318, of March 31, 1942, to provide water-tight closures with quick-acting locking mechanism and accordingly the same is not claimed broadly herein, the claims being confined to the novel features of my improved closure which impart thereto some or all of the various advantages possessed thereby as herein set forth.

My invention is fully set forth in the following detailed description and drawings forming a part thereof, in which latter,

Figure 1 is an elevation, partially cut away, of a water-tight bulkhead door of a ship, the same embodying a preferred form of the invention;

Figure 2 is an enlarged detailed section, taken on the line 2—2 of Figure 1; and Figure 2^a is a similar view showing a modification wherein the door frame is offset in order to economize in space;

Figure 3 is an enlarged detail section, taken on the line 3—3 of Figure 1, showing the locking mechanism in a closed position; and Figure 4 is a similar view, except that the locking mechanism is shown in an open position;

Figure 5 is an enlarged detail transverse section, taken on the line 5—5 of Figure 6;

Figure 6 is an enlarged detail longitudinal section taken on the line 6—6 of Figure 1;

Figure 7 is a longitudinal section, taken on the

2

line 7—7 of Figure 6, the sealing gasket being omitted for better illustration;

Figure 8 is a fragmentary detail section showing the manner in which the operating handle 5 is mounted on the shaft of the locking mechanism whereby an air-tight joint is provided therebetween;

Figure 9 is a fragmentary detail section showing a still further modification of the locking mechanism;

Figure 10 is an enlarged, fragmentary elevation of an adjusting screw element, such as shown in Figure 9, which may be employed in the locking mechanism of my improved door;

Figure 11 is an elevation, generally similar to Figure 1, wherein one of the operating handles is positioned substantially centrally of the door panel and the other in close proximity thereto;

Figure 12 is a transverse section taken on the line 12—12 of Figure 11; and

Figure 12^a is a similar view but showing a modification wherein the door frame is offset to bring the same flush with the door panel;

Figure 13 is a fragmentary detail vertical section of the door hinge, taken on the line 13—13 of Figure 11; and Figure 13^a is a similar view taken on the lines 13^a—13^a of Figure 12^a;

Figure 14 is an enlarged longitudinal elevation showing the latch for the operating handles;

Figure 15 is a fragmentary transverse section showing a modification of the mounting of the shaft of the locking mechanism;

Figure 16 is a view generally similar to Figure 6 but showing a modification of the locking mechanism;

Figure 17 is a transverse section taken on the line 17—17 of Figure 16; and

Figure 18 is a view generally similar to Figure 16 but showing a still further modification.

Referring to the drawings and the construction disclosed therein, the reference numeral 1 designates a water-tight bulkhead door, the same having a main unpierced closure panel 2 of generally elliptical configuration and a continuous marginal flange 3 that is integral therewith. The door is mounted on hinges 4 carried by the door frame 5 and the latter has a terminal flange 6 and a continuous channel member 7 formed thereon for the reception of a continuous sealing gasket 9 which is snugly fitted therein.

A shaft 10 is journalled at one end in a bearing block 11 mounted on the flange 3 and at its other end in a nut 12 which is threaded thereon and welded on the outer face of said flange 3. The portion 13 of the shaft is of reduced section to

admit of the reception of a compressible sealing gasket 14 thereon. Beyond such reduced portion, the shaft is of similar cross section to the portion on which the nut 12 is mounted and is threaded to receive a second nut 15 which has a terminal recess 15' to admit of the projection thereinto of the outer end of said gasket. A set screw 16 serves to lock said latter nut in any desired adjusted position on said shaft.

A handle member 17 is fixed on one end of said shaft and a second handle member 17' is mounted on the same shaft intermediate the lateral margins of the door 1. The handle 17 has a sleeve 18 slidably mounted thereon, the same having marginal recesses 18' adapted to receive the shank of a locking thumb-screw 19. Said sleeve carries a T-shaped hook 20 that is adapted to be projected through eyes *a* of apertured lugs 21 and 21' carried by said flange 3 to thereby maintain the shaft vertically in either a locked or unlocked position. As is evident, the thumb-screw 19 is tightened after the hook element has been projected through a co-operating eye *a* as a result of the manual longitudinal adjustment of the position of the sleeve 18 on the handle member 17.

Two pairs of opposing slotted lugs 25, 25' are carried by said shaft adjacent the ends thereof, the same being either welded or otherwise fixed thereon. Two pairs of oppositely extending link members 26 and 26' are respectively mounted in the slots of said lugs, the same being pivotally connected thereto by pins 27. Said links at their opposite ends are respectively mounted in terminal slots 28 of thrust rods 29, being pivotally connected thereto by pins 30. These rods project through circular apertures *b* formed in guide plates 31 that are welded or otherwise fixed to the inner face of the flange 3 and panel 2. Each rod is desirably slightly offset adjacent its end and is adapted, when the thrust rod is in its extreme outermost position, to project through an aperture *c* in a second guide plate 32 that is also welded or otherwise secured to the inner face of said flange 3 and the door panel.

Each thrust rod has a pair of dogs 35 and 36, welded or otherwise fixed thereto, the dog 35 being positioned adjacent the rear end of the thrust rod and the other dog adjacent the outer end thereof. Each of the dogs is of a suitable configuration to engage the outer end of a set screw 37 having a jam nut 37' and which screw is obliquely mounted in a keeper or support platen 38 that is welded or otherwise fixed to the inner face of the flange 6 and to the adjacent face of the channel member 7, the same bridging the gap therebetween.

In the modification illustrated in Figures 9 and 10, the thrust rods are formed in a plurality of sections 40, 40^a and 40^b interconnected by shouldered couplings 41, thereby admitting of the longitudinal adjustment of the thrust rods whereby intimate engagement between the dogs carried thereon and their respective keepers is not only always insured but also such dogs can be caused to so engage their respective keepers successively, rather than simultaneously, with the consequence that the amount of pressure required to effect locking engagement therebetween is substantially reduced or lessened.

In Figure 11 as well as in Figures 12 and 12^a, the handle member 42 is mounted centrally of the door panel 43 so as to lie wholly within the channel 44 of the panel when moved into a vertical position, namely when the locking mecha-

nism is either locked or unlocked. The second handle member 42^a is mounted behind the door panel and to one side of such channel.

In Figures 2^a and 12^a the door frame 45 is offset to not only reinforce the same but also for the purpose of economizing in space.

In Figures 16 and 17, the keeper element which co-operates with the dog element 50 constitutes a roller 51 that is rotatably mounted on a pin 51' whereas in Figure 18 the inner-face of the dog 52 is of angular configuration along the upper portion of its inner face, as indicated by the reference numeral 53, and as a consequence is adapted to snugly engage a flat keeper member 54 having a beveled edge 55.

In Figure 15 is illustrated a modified form of stuffing box for the shaft 60 of the locking mechanism, the same comprising an outer sleeve 61 which projects through the flange 44 of the door panel and is welded thereto. Bushings 62 and 62' are oppositely disposed with respect to a cylindrical layer of fibrous lubricated packing material 63. An apertured terminal cap 64 which is threaded on the end of said sleeve is adapted to engage a washer 65 and maintain the same in continual pressure engagement with the outer end of the bushing 62', thereby maintaining said packing in intimate contact with said shaft and hermetically sealing the joints between the shaft and bushings and between the latter and the sleeve 61.

The manner of operation of my improved closure illustrated in Figure 1, as will be apparent from the foregoing description, is as follows:

When it is desired to seal the bulkhead opening, the thumb-screw 19 is unscrewed to release the sleeve 18 and the latter is manually moved a sufficient distance upwardly along the operating arm 17 to disengage the hook 20 from its co-operating lug. Thereupon the said handle is turned anti-clockwise to effect rotation of the shaft 18 in the direction indicated by the arrow in Figure 3 and such rotation is continued until the thrust rods 29 assume the positions shown in Figures 1 and 3 at which time, owing to the fact that the pins 27 will have passed a dead center, i. e., beyond the lines corresponding to extensions of the longitudinal axes of the thrust rods 29, the dogs 35 and 36 will have receded slightly from the extreme forward positions thereof and as a consequence of such movements any tendency for the dogs to rattle or become disengaged from their associated set screws 37, due to vibrations imparted thereto by the ship's propeller or otherwise, will be substantially prevented or at least minimized. The engagement of the cam-like inner faces of the dogs 35 and 36 with their associated set screws carried by the keepers 38 causes the marginal edge of the panel flange 3 to effect intimate engagement with the gasket 9 and thereby insures the hermetic sealing of the joint between the closure 1 and the frame 5. When such joint has been so sealed, the sleeve 18 is manually moved along the arm 17 in such a manner as to admit the hook member 20 to assume the position shown in Figure 1 and the thumb-screw 19 is screwed home, thereby effectively holding the locking mechanism in the locked position shown in Figure 1. As shown in Figure 2, the pintles *d* of the hinges project through slots *e* in the hinge leaves and thereby sufficient inward movement of the door panel 1 is permitted to insure the aforesaid intimate sealing engagement of the peripheral edge of the flange 3 with the gasket 9.

In order to open the bulkhead door, the thumb-screw 19 is unscrewed sufficiently to admit of the movement of the sleeve 18 longitudinally of the arm 17 and the consequent disengagement of the hook 20 and the associated lug 21. The handle 17 is then manually turned clockwise, as indicated by the arrow in Figure 4, thereby withdrawing the dogs 35 and 36 from engagement with their respective keepers 38 and permitting of the unhindered opening of the closure member 1. Following the opening of the door, the sleeve 18 is then manually moved along the handle 17 until the hook 20 engages the eye *a* in the lower lug 21' and the thumb-screw is then again screwed home to maintain the sleeve in such adjusted or locked position.

The operation of the mechanism shown in Figs. 9 and 10 is generally similar to that just described except that the couplings 41 may, if desired, be adjusted so that the dogs carried by the sectional thrust rods 40, 40^a, 40^b will successively engage their respective keepers 38 or the modified forms of keeper elements illustrated in Figs. 16 and 18 should same be employed. In the construction shown in Fig. 9, the locking sleeve element as well as the associated hook and co-operating apertured lug illustrated in Fig. 1 have been omitted for clearness of illustration but preferably the same is also employed in both forms of the forms of locking mechanism illustrated in these two views.

The continuous marginal flanges 3 and 6 are of similar configuration, the latter being enveloped by the former when the door panel is closed. The locking mechanism which, with the exception of the operating handles and the contiguous portions of the main shaft, is concealed from observation from either side of the panel is not susceptible to being dis-aligned and rendered inoperative should the door panel be struck by cargo when the same is being either intentionally or accidentally shifted as in stormy weather, for example, and in this respect is quite different from locking mechanism in common use wherein centrally disposed hand wheels are mounted on a central stud shaft which projects through the panel and such wheels are connected by gearing or radiating linkage to the various dog elements. Furthermore, owing to the fact that the locking mechanism is located marginally of the door, the operation of the actuating dogs in my improved closure construction is necessarily more direct and requires less pressure than in those constructions wherein the mechanism is operated by a centrally disposed hand wheel and co-operating gearing or radiating linkage.

Since the door panel in my closure construction is unobstructed by underlying linkage or gears and carries no hand wheels whatsoever, the same may, if desired be equipped with supplemental escape or scuttle openings of a size, for example, as indicated by the diagrams *f* and *f'* in Figs. 1 and 11 and which openings may be sealed by almost any type of closure since obviously they are not required to be of a quick-acting character. Moreover, because the door panel in my construction of closure is unpierced and especially sturdy as contrasted with thin or light gauge cover plates often used in prior constructions in an effort to conceal the locking mechanism, it is ideally adapted to withstand heavy blows from either side thereof and to effectually shield the concealed mechanism from the effects of any such blows.

In the form of roller keeper and camming dog construction shown in Fig. 16 and Fig. 17, the co-operating camming action thereof serve to effect a quick application of the pressure applied to the crank arms or operating handles and to effectively compress the marginal gasket as a result of such action even though the door panel has been but lightly closed against the gasket without any especial exertion by the operative 10 whereas in the ordinary quick-acting closure for bulkheads considerable pressure must be manually applied to the door panel in order to cause the marginal dogs of the mechanism to effectively and properly engage their co-operating 15 keepers.

Various changes in the herein-described closure construction may be made without departing from the spirit of my invention as embraced within the scope of the appended claims.

Having thus described my invention, what I claim is:

1. In a quick-acting closure for securing a bulk-head door, hatch or like closure to its frame, the combination of a closure of the character specified having a longitudinal channel disposed intermediate the opposite sides thereof, a flange member carried by and extending completely around the margin of such closure, an apertured frame member to which such closure is pivotally 25 connected and which extends marginally thereof, said frame member being rigidly mounted independently of such closure, a main shaft carried by such closure, the same extending through the sides thereof and across said channel and being 30 supported at its opposite ends by said continuous marginal flange on the closure; co-operating means including thrust rods operatively connected to said shaft and keeper elements carried by said frame for locking said closure in pressure 35 engagement with said frame when the closure is closed against the same, said thrust rods and said keeper elements being substantially entirely concealed between the frame and the closure; and a pair of crank arms mounted on said shaft, accessible 40 to operatives stationed on either side of said closure and operatively connected to said shaft, for effecting oscillation thereof, one of them being secured to a portion of the shaft which extends across said channel and the other being 45 disposed to one side of said channel.

2. In a quick-acting mechanism for securing a bulkhead door, hatch or like closure to its frame, the combination with such a closure of a flange member carried by and extending completely 55 around the margin thereof, an apertured frame member to which such closure is pivotally connected and which extends marginally thereof, said frame being rigidly mounted independently of said closure, a main shaft extending across 60 said closure and having its ends journalled in opposite sides of said flange member; cooperating means including thrust rods operatively connected to the shaft and keeper elements carried by said frame for locking said closure in pressure 65 engagement with the frame when the closure is closed against the same, said thrust rods and said keeper elements being substantially entirely concealed between the frame and the closure and said thrust rods being each equipped with a plurality of dog elements having cam-shaped faces adapted to have wedging engagement with the keeper elements when the thrust rods are in an extreme outermost position; and crank arms accessible 70 to operatives stationed on either side of

said closure and operatively connected to said shaft for effecting oscillation thereof.

3. In a quick-acting mechanism for securing a bulkhead door, hatch or like closure to its frame, the combination with such a closure of a flange member carried by and extending completely around the margin thereof, an apertured frame member to which such closure is pivotally connected and which extends marginally thereof, said frame being rigidly mounted independent of said closure, a main shaft carried by said closure; co-operating means including sectional, adjustable thrust rods operatively connected to the shaft and keeper elements carried by said frame for locking said closure in pressure engagement with said frame when the closure is closed against the same, said keeper elements being substantially entirely concealed between said frame and the closure, guide members on the marginal flange of said closure which support said thrust rods, crank arms accessible to operatives stationed on either side of said closure and operatively connected to said shaft for effecting oscillation thereof; and latching means for maintaining the

crank arms in positions corresponding to either a locked or unlocked position of said thrust rods and keeper elements.

ARTHUR S. WIEDERMAN.
